UNITED STATES PATENT OFFICE.

ALFRED A. HENTZELL, OF LITTLETON, COLORADO, ASSIGNOR TO INGERSOLL-RAND COMPANY, OF JERSEY CITY, NEW JERSEY, A CORPORATION OF NEW JERSEY.

DIE FOR DRILL-SHARPENING MACHINES.

Application filed June 30, 1922. Serial No. 571,882.

To all whom it may concern:

Be it known that I, ALFRED A. HENTZELL, a citizen of the United States, and a resident of Littleton, county of Arapahoe, 5 and State of Colorado, have invented a certain Die for Drill-Sharpening Machines, of which the following is a specification accompanied by drawings.

This invention relates to drill sharpening 10 or forging machines and particularly to upsetting and forming dies used in such machines for imparting a desired conformation to the ends of rock drill steels, such, for instance, as required in forming collars or 15 lugs.

A forging or drill sharpening machine of the type adapted to form lugs or collars on rock drill steels is shown in my prior Patent No. 1,223,975 granted April 24, 1917, 20 wherein the main holding dies which are fitted to the stationary and movable jaw members in the machine to adapt the machine for the purpose mentioned, also act as bushings and receive the impact of the 25 percussive element incident to the operation of upsetting the end of the drill steel. Hence, these dies are directly subject to 30 shock and wear rapidly, necessitating complete replacement when deformed. This is expensive and otherwise unsatisfactory.

The primary object of the present invention is to enable the bushings which bear the shock and wear in the forming operations to be easily, quickly and cheaply replaced or renewed, without replacing or renewing the main holding dies or affecting their adjustment in any way.

Another object is to retain the bushings and plunger dies in the main holding dies 40 against unintentional displacement. A further object is to enable the removable bushings and plunger dies to cooperate in defining the forming recess. Still further objects will later appear and to all the ends 45 herein set forth the invention consists in the features of construction and operation described in the following specification and illustrated in the accompanying drawings, forming a part hereof, in which—

50 Figure 1 is a side elevation partly in section of a drill sharpening machine embodying the invention;

Figure 2 is an enlarged detail longitudinal

sectional view of the main holding dies and 55 forming dies;

Figure 3 is a transverse sectional view taken on the line 3—3 of Figure 2;

Figure 4 is a perspective view of one of the main holding dies; and

Figure 5 is a perspective view of one of 60 the removable bushings.

In the drawings the invention is shown in connection with a drill sharpening machine which in its essential characteristics is similar to the machine illustrated in my prior 65 patent referred to. The drill sharpening machine includes a base A supporting a stationary lower clamping jaw B and a movable upper clamping jaw C, the jaw C being mounted on a vertically reciprocable plunger (not shown). An arm D extends from the base and a percussive element in the form of a pneumatically actuated tool E is adapted to be mounted on the arm D, so that the reciprocable dolly F is in alignment with 70 the space between the opposing surfaces of the jaw members B and C. The jaws B and C are adapted to be brought close together for performing various operations upon the 75 drill steel. One such operation is that of cutting or severing the lengths of drill steel, and for this purpose cooperating cutters G are secured on the jaws B and C at the front 80 of the machine by bolts H.

Upper and lower die holder guides or 85 seats J are fitted over the opposing surfaces of the jaws B and C. These seats are provided with offset portions K and turned ends L, and are adapted to be inserted in the jaws B and C so that the rearwardly 90 inclined shoulders O on the seats J abut against similarly inclined shoulders P on the jaws, thus rigidly securing the seats J against longitudinal movement in the direction opposite to the percussive tool E. The 95 turned ends L are secured to the jaws B and C by bolts Q.

The inner opposing surfaces R and S of the die seats J in the jaws B and C respectively, are semi-circular and together form a longitudinal circular recess, for receiving and retaining the longitudinal main holding dies and forming dies in place between the jaws B and C. The main holding dies T are approximately semi-circular in cross 105 section, the outer surfaces U being provided

with webs or flanges V having inclined sides v which fit semi-circular undercut recesses W in the opposing die seat surfaces R and S. The main holding dies T are thus retained in the die seats J against longitudinal movement, and the main holding dies in turn retain the forming dies, which include bushings and plunger dies.

The inner surfaces of the main holding dies T form longitudinal semi-cylindrical grooves or recesses Y and at the sides of these grooves Y are longitudinal beveled ribs Z. A pair of removable semi-cylindrical bushings a are adapted to be inserted longitudinally in the recesses Y, these bushings a being cut away at their longitudinal outer sides as shown at b in correspondence with the beveled ribs Z in the recesses Y, so that the bushings are retained in the recesses Y against vertical or transverse movement. Locking pins d are adapted to pass through central holes e in the main holding dies T and into corresponding holes or recesses f in the bushings a to hold the bushings against longitudinal movement. For a portion of their length the bushings a are provided with opposite longitudinal recesses g which are adapted to effect clamping engagement with the shank of a drill steel p. Adjacent to one end, however, the recesses g are enlarged so that together they form an upsetting recess h. Swaging means I are adapted to cooperate with the bushings a. In the present instance the swaging means comprise a pair of upper and lower plunger dies j adapted to be inserted longitudinally within the recesses Y of the main holding dies T in the same manner as the removable bushings a, but such swaging means I may consist of a single plunger die or may be otherwise formed. The bushings a and swaging means I constitute the forming dies for imparting the desired conformation to the end of a rock drill steel or other article. The plunger dies j are of relatively less length than the bushings a and have opposite internal recesses k extending longitudinally for a portion of their length adapted to accommodate the sides of the end of the drill steel p, the extreme end of the drill steel p abutting against the shoulders q within the plunger dies j. The inner ends of the plunger dies j, the recesses k and the outer walls of the upsetting recess h are adapted to cooperate and act as forming surfaces and recesses for the purpose set forth herein. In the present instance the forming dies are adapted to forge a lug or collar adjacent to the end of a drill steel shank. The drill steel is securely held between the bushings a and plunger dies j when the jaw member C is lowered, the steel having first been heated and inserted the required distance. The percussive tool E is then operated to cause the dolly F to reciprocate rapidly against the outer ends of the

swaging means I in this case the plunger dies j, forcing the metal into the upsetting recess h, the walls of which recess h are defined by the adjacent ends of the bushings a and swaging means I, and the lug or collar 70 is formed on the steel under the swaging pressure administered through relative movement of the forming dies.

In assembling the dies the bushings a are inserted longitudinally in the recesses Y of the main holding dies T to the limit of their movement against shoulders r and the pins d are passed through the aligned holes e and recesses f. The plunger dies j are similarly inserted, but are freely movable longitudinally. The main holding dies T are then held so that the webs V are aligned with the recesses W in the die seats J and are then slid transversely into place in the die seats, the movable jaw of the sharpener having first 85 been raised to its uppermost position. When thus inserted the outer edges of the bushings, main holding dies and die seats in each group are in parallel alignment and form plane opposing surfaces.

The points of rapid and greatest wear in a machine of the character described are the surfaces of the bushings which are subject to the swaging pressure exerted by the plunger dies under the influence of the percussive 95 tool. When such bushings are integral with the main holding dies, or when the bushing surfaces are formed on the main holding dies themselves, as in my prior patent referred to, it becomes necessary to replace the main holding dies at more or less frequent intervals. This is an expensive proceeding which the use of separate removable bushings as shown, described and claimed herein, avoids. The bushings are comparatively inexpensive and a supply can be kept on hand so that no time is lost in the operation of the machine.

I claim:

1. In a drill sharpener, a pair of relatively 110 movable jaws, die holder guides fitted over the opposing surfaces of said jaws, holding dies in said guides, said guides and holding dies having cooperative flanges to retain the holding dies in the guides, a pair of die bushings in said holding dies, a pair of plunger dies slidable in said holding dies, longitudinal ribs to retain said bushings and plunger dies within said holding dies, and locking pins adapted to pass through said holding dies to hold the bushings in a fixed position with relation to said holding dies.

2. In a drill sharpener, the combination of 115 relatively stationary and movable jaws, cooperating main holding dies carried by said jaws, and forming dies in said holding dies adapted to act on a drill steel, said forming dies including a pair of upper and lower semi-circular bushings longitudinally insertable and slidable in said holding dies and 120

125 130

- adapted to effect clamping relationship with said drill steel, a pair of cooperating semi-circular plunger dies slidable in said holding dies and adapted to fit over and abut 10 against the end of a drill steel held between said bushings, and locking pins passing through said main holding dies into said bushings, said bushings being provided with recesses corresponding to the form of collar desired to be upset on the shank of the 10 drill steel, and said plunger dies having forming surfaces cooperating therewith.
- 5 In testimony whereof I have signed this specification.

ALFRED A. HENTZELL.
